UNITED STATES PATENT OFFICE.

ERNEST M. WENZEL, OF KANSAS CITY, MISSOURI.

GARMENT-STRETCHER.

1,277,010.

Specification of Letters Patent. Patented Aug. 27, 1918.

Application filed September 22, 1917. Serial No. 192,798.

To all whom it may concern:

Be it known that I, ERNEST M. WENZEL, a citizen of the United States, residing at Kansas City, in the county of Jackson and 5 State of Missouri, have invented certain new and useful Improvements in Garment-Stretchers, of which the following is a full and exact specification.

The present invention relates to improvements in garment stretchers, and more particularly to devices for holding in shape the leg portions of trousers, and aims to provide a stretching device for this purpose which will be both effective and convenient 15 in its operation.

It is also sought to devise a construction wherein is provided a range of adjustment both as regards the stretching action as well as for adapting the device for varying sizes 20 of garments.

It is also an object to provide a device of this character having a yielding operating means for holding the parts in their operative or expanded relation.

25 A further object is to devise an arrangement and construction which will be extremely practical and durable and of a nature which will be cheap to manufacture. Minor objects will appear in the course 30 of the detailed description.

With these objects in view the invention will now be described with reference to the accompanying drawing wherein is illustrated one form of construction which has 35 been devised for carrying out the desired objects of the invention, after which the improved features will be set forth and defined in the appended claims.

In the drawing—

40 Figure 1 is a plan view of a stretching device constructed in accordance with the present invention, the dotted lines representing the parts in expanded relation;

45 Fig. 2 is a side or edge view of the device, with certain portions broken away; and

Fig. 3 is an end view of the same.

Referring to the drawing in detail, the device is illustrated as comprising a pair of 50 longitudinal side pieces 4, of light but strong material, constituting the garment-engaging members, and preferably formed with thin outer edges (see Fig. 2) designed to fit in the creases of the trousers legs. The 55 opposite ends of each of the members 4 are rabbed to provide kerfs 6 within which to

pivot, by means of screws 8 or the like, one end of each of the curved toggle links 10 and 12, arranged in pairs at the opposite ends of the members 4. The upper pair of 60 links 10 are somewhat longer than the links 12 in order to provide for the greater expansion required at the upper portion of the trousers legs. The bottoms of the kerfs 6 serve to limit the expanding movement of 65 the links.

The links 10 are connected to form a toggle joint by means of a bolt 14 carried by the legs of a yoke member 16 straddling the links 10, said bolt being adapted to be fitted 70 through any one of the pairs of bolt openings 18 provided in said links 10, whereby the throw as well as the leverage of the toggle are regulated.

The lower links 12 are connected to form 75 a toggle joint by means of a bolt 20 which is adapted to be fitted through any one of the pairs of bolt openings 22 provided in said links 12, thus obtaining a similar adjusting arrangement as regards the toggle 80 action at this end of the device.

To the yoke 16 is connected one end of a coil spring 24, to the other end of which is connected a strap link 26 provided with a series of bolt openings 28, whereby, when 85 the device is expanded, said link 26 may be adjustably connected to the lower toggle joint by hooking said link over the projecting end of the bolt 20.

The operation of the stretching device 90 will be readily understood by reference to Fig. 1. With the device contracted and the parts occupying the positions illustrated by the full lines in said figure, with the strap link 26 disconnected from the lower toggle 95 joint, the device may be inserted into position within the trousers leg for engagement of the side edges of the members 4 with the lines of the trousers creases. The upper toggle links are then expanded by drawing the strap link 26 in the direction of the lower toggle links 12, the latter being at the same time expanded by the operator by moving its toggle joint in the direction of said link 26 preparatory to hooking the link 26 100 over the bolt 20. When the link 26 and bolt 20 are properly connected, as represented by the dotted lines in Fig. 1, the parts are held securely in their proper position with a strong, yet yielding, action due to the 110 pull of the spring 24, which serves to take up any "give" in the goods of the gar-

ment and maintain a constant effective engagement of the side members 4 therewith. The arrangement of toggle links is one which is particularly effective for the purpose of spreading the side members 4 in expanding the device, the straightening action of said toggles exerting a strong leverage under the pull of the spring without requiring a very great degree of movement of the joints. Furthermore, the adjustability of the toggle joints and of the connection between the sets of toggles provides for all necessary variation in the toggle action as well as for the varying degrees of expansion required for different sizes of garments.

It will thus be seen that a simple and efficient arrangement and construction have been devised for carrying out the desired objects of the invention, and while the foregoing represents what is now deemed to constitute the preferred form of construction, the right is reserved to make such formal changes and modifications as may fairly fall within the scope of the appended claims.

What I claim is:

1. A trousers stretching device adapted to be inserted within the leg portions of trousers comprising a pair of side members 30 formed with substantially straight outer edges adapted for engagement with the crease lines of the trousers leg, an expanding mechanism associated with each end of the device and connected to the ends of said members and operable, by relative approaching movement of said mechanisms toward each other, to spread said members, and yielding means detachably connecting said mechanisms and acting to hold the same in 40 yieldingly expanded relation.

2. A trousers stretching device adapted to be inserted within the leg portions of trousers comprising a pair of side members formed with substantially straight outer 45 edges adapted for engagement with the crease lines of the trousers leg, a toggle mechanism associated with each end of the

device and connecting the ends of said members, the toggle joints of said mechanisms moving toward each other in expanding the 50 device, and means detachably connecting the toggle joints of said mechanisms to each other and including a yielding element, said connecting means tending to straighten said toggle mechanisms and hold said stretching device in yieldingly expanded relation. 55

3. A garment stretching device comprising a pair of side members, a toggle mechanism associated with each end of the device and connecting the ends of said members, 60 each toggle mechanism comprising a pair of oppositely arranged semicircular toggle links provided each with a series of bolt openings, and a pivot bolt adapted to be adjustably mounted in said openings, the toggle 65 joints of said mechanisms moving toward each other in expanding the device, and means detachably connecting the toggle joints of said mechanisms to each other and including a yielding element tending to 70 straighten said toggle mechanisms and hold said stretching device in yieldingly expanded relation.

4. A garment stretching device comprising a pair of side members, a toggle mechanism associated with each end of the device and connecting the ends of said members, each toggle mechanism comprising a pair of toggle links, the toggle joints of 75 said mechanisms moving toward each other 80 in expanding the device, the ends of said side members being formed with kerfs receiving the outer ends of said links and the bottoms of said kerfs limiting the straightening movement of said toggle mechanisms, 85 and means connecting the toggle joints of said mechanisms to each other and including a yielding element tending to straighten said toggle mechanisms and hold said stretching device in yieldingly expanded relation. 90

In witness whereof I affix my signature.

ERNEST M. WENZEL
